UNITED STATES PATENT OFFICE

JOHN ELLIS OSTLINE, OF CHICAGO, ILLINOIS, REGINALD TAYLOR, OF LIVERPOOL, AND CHARLES EDMUND BEALE, OF LONDON, ENGLAND, ASSIGNEES TO ASSOCIATED TELEPHONE AND TELEGRAPH COMPANY, OF CHICAGO, ILLINOIS, A CORPORATION OF DELAWARE

TELEPHONE SYSTEM

Application filed April 14, 1930, Serial No. 444,022, and in Great Britain May 1, 1929.

The present invention relates to telephone systems and is more particularly concerned with systems including both manual and automatic exchanges in which case it is necessary to provide special equipment for setting up calls from manual to automatic exchanges and vice versa. The invention is concerned only with the setting up of calls from a manual exchange to an automatic exchange and relates to special trunking arrangements whereby this may be done direct from an A operator's position without the necessity for handling by a B operator located in the automatic or some intermediate exchange.

The simplest method of operation is to provide the A operator with a dial which can be connected with any cord circuit at her position and by means of which she transmits impulses over the trunk to be used for the connection which she herself selects by means of the usual tests. This arrangement, however, may be objectionable in certain cases owing to the necessity for some considerable changes in the standard cord circuits used for pure manual calls and moreover the use of a dial is somewhat laborious and rather slow. Accordingly arrangements have already been proposed whereby the operator is provided with a keyset which however generally necessitated either the provision of a considerable amount of equipment in the manual exchange, which is undesirable, or the transmission of special pulses involving the use of marginal or polarized relays. It has also been proposed that the particular trunk which was to be used for a call should be selected by an automatic switch and indicated to the operator on a lamp panel or the like.

The object of the present invention is to provide an improved arrangement whereby the operator herself selects the junction which will be used so that no lamp panel or similar additional equipment is necessary at her position while the determination of the impulses to be transmitted is effected from a key-set over a four conductor keying trunk.

According to one feature of the invention in a system including both manual and automatic exchanges and having calls from a

manual exchange set up by an A operator by means of a key-set, the momentary operation of a key is adapted to effect the association of the key-set with a common control line to an automatic exchange, the association being maintained until the full number has been registered at the automatic exchange or a release key is operated. 55

According to another feature of the invention a line extending to an automatic exchange and common to a plurality of operators has associated with it a hunting switch which is adapted to be set in operation when a junction to that exchange is seized to associate the line with the junction seized by 60 the operator whose key set is then associated with the line. 65

A further feature of the invention is that the operator selects a free junction leading to a particular automatic exchange and then 70 operates a key corresponding to that exchange whereupon due to a special connection over one conductor of the junction, the junction selected is automatically associated at the incoming end with a common control line extending to that exchange. 75

The invention will be better understood from the following description of several methods of carrying it into effect which should be taken in conjunction with the accompanying drawings. It will be understood, however, that the invention is not limited to the specific embodiments shown and that various alterations to the circuit details such as may readily be carried out by 80 those skilled in the art would come within its scope. 85

Referring now to the drawings, Figs. 1-7 show detailed circuits of this arrangement. Of these drawings, Fig. 1 shows the keys at 90 the operator's position and the jack terminating one junction together with the trunk finder switch for associating the operator's key-set with the keying trunk corresponding to the order wire key depressed. Fig. 2 shows the trunk relay set at the incoming end 95 of the junction, together with the junction finder switch for associating the keying trunk with the junction. Fig. 3 shows the sender finder for associating a free register 100

sender with the junction. Figs. 4, 5, 6 and 7 show the detailed circuits of a suitable sender.

In the arrangement illustrated in Figs. 1-7 the method of operation is that the operator keeps the order wire key depressed until she secures control of the order wire as indicated by the lighting of the guard lamp associated therewith and then tests in the multiple for a free junction. This arrangement is open to the objection that the order wire is being held during the time that the operator is making her test for a free junction and this time will probably be comparable with and may even exceed the actual time taken to key up the number. Accordingly, Figs. 8 and 9 show a modification whereby the operator first plugs into a free junction and then presses the order wire key so that as soon as she obtains control of the order wire she may key up the number and thus more economical use is made of the order wire.

Figs. 10-12 show a further modification in which the junction finder switch at the automatic exchange has been eliminated, the order wire being associated with the required junction by means of a switching relay, the circuits being such that it is impossible for the order wire to be associated with two junctions at the same time. Fig. 13 shows diagrammatically the general layout of the system illustrated in Figs. 1-7.

The operation of this system may first be traced through briefly with reference to Fig. 13. Assume that an operator at position 1 having ascertained the requirements of a calling party wishes to set up a connection to the automatic exchange shown, she will depress the order wire key 01 momentarily, whereupon the associated keying trunk finder TF1 will start hunting under the control of the position relay set PRS to associate its wipers with the keying trunk KT extending to the required exchange and when this has been done, guard lamp L1 will commence to flicker. In the meantime the operator will test in the usual way for a free trunk outgoing in the required direction and having found one will plug into the corresponding jack J1. Thereupon circuits completed over the trunk T for relays in the trunk relay set TRS will cause the sender finder SF associated therewith to select a free sender S and at the same time the first selector E will be prepared for operation. Meanwhile or as soon as a free sender has been associated with the trunk relay set, the finder RF associated with the keying trunk relay set KTS will operate to connect the keying trunk with the trunk relay set TRS. This operation of course will only take place assuming that the keying trunk KT is not already in use and if it should happen that another operator is using the keying trunk at this time, the operator under consideration will have to wait

until it becomes free. When the operator obtains connection with the keying trunk, that is to say, when the switch RF finds the trunk relay set TRS, the operator will receive two short tone signals and she will then commence to operate the keyset K1 for the four digits of the wanted number. This effects the connection of suitable potential to the four leads of the keying trunk in various combinations and since these leads are now extended through to the sender, it will now send out the appropriate trains of impulses for operating the selector E and suitable succeeding switches. Conveniently the sender commences sending as soon as the first digit has been registered since this reduces the holding time of the senders and hence enables the number required to be kept as small as possible. The keyset is disconnected from the keying trunk and the guard lamp is extinguished as soon as the call has been completely set up. Supervision of the call is effected as on manual-to-manual calls.

In case the operator should realize that she has made an error in setting up the number, she will cancel by withdrawing the plug from the trunk jack, depressing the order wire key again momentarily and replacing the plug, in consequence of which the operated apparatus is released and the setting up of the call may take place correctly in the manner previously described. This arrangement readily permits cancellation to take place at any stage of the setting-up operation without introducing a large amount of complicated equipment.

It may be mentioned that if the manual exchange had access to only four or less automatic exchanges, it would probably be preferable to employ relay switches in places of the rotary type keying trunk finders shown. Considering now the detailed operation of the circuits shown in Figs. 1-7, it will be assumed that the operator on receiving a call plugs into the answering jack of the calling subscriber with the answering plug of a cord circuit of known type and ascertains that he requires connection to a subscriber attached to a particular automatic exchange. She will thereupon depress the order wire key associated with this exchange which will be assumed to be that shown in Fig. 1 and designated 01, whereupon a circuit will be completed from earth over the lower springs of the key, high resistance right-hand winding of relay KT, armature *kt1*, interrupter springs *tm1*, very high resistance winding of relay GT to battery. Relay GT alone operates in this circuit and at armature *gt1* completes a circuit for the driving magnet TM of the trunk finder switch TF, whereupon the magnet operates and at the interrupter contacts *tm1* opens the circuit of relay GT. Furthermore at the upper springs of the key 01 battery through the winding of relay TS is

extended over armature $tr1$ to the associated contact in the bank of wiper P. The interaction between relay GT and driving magnet TM advances the wipers of the trunk finder switch TF until they encounter the marked bank contact whereupon relay GT will be shunted out in a circuit including the low resistance left-hand winding of relay KT, the wiper and bank P and winding of relay TS to battery. Since relay GT cannot again operate, the switch is brought to rest and relays KT and TS are operated in series, the former at armature $kt1$ completing a holding and guarding circuit by way of its low resistance left-hand winding to earth at the release key R. In order that there shall be no possibility of one operator being connected with a keying trunk which has been marked by another operator, the P banks of the trunk finder switches TF at the various positions are not commoned together, so that the depression of an order wire key similar to 01 on any position only results in the marking of the appropriate bank contact of the trunk finder switch associated with that position. When, however, the trunk has been actually taken into use, the operation of relay TS at its various armatures (of which there will be one per switch) establishes connection with all the corresponding bank contacts of the other switches, thereby busying this particular trunk to all the operators. This operation also completes a locking circuit for relays TS and KT so that the order wire key may now be released. The operation of relay KT moreover at armatures $kt2$ — $kt5$ connects up the keyset numbered 1 to 0 by way of the wipers of the trunk finder switch TF to the selected keying trunk in readiness for the required number to be set up by the operator, while at armature $kt6$ interrupted earth of conveniently 2 secs. on and 2 secs. off is connected to the position guard lamp FL, thereby indicating to the operator that she may now release the order wire key 01 and proceed to test in the usual manner for a free junction leading to the required exchange. In order to simplify and shorten the process of testing for an idle junction it may be desirable in some cases to employ known group testing arrangements for instance those employing chain contacts on the sleeve relays such as S by means of which a special relay may be operated when the chain is complete to effect the connection of discriminating tone to a master jack to indicate that all the lines of the group are busy.

In case all the junctions should happen to be busy at this time, the operator will be unable to set up the connection and will momentarily press the release key R to free the keying trunk. Thereupon relays KT and TS are de-energized and the connection of the operator's keyset to the keying trunk is broken so that she may proceed with the setting

up of another call and moreover the keying trunk is rendered available to other operators.

When the operator has found a free junction to the required exchange, for instance that shown, she will plug in to the associated jack thereby extending battery from the cord circuit over the ring conductor 11 to operate relay L in the junction relay set JR, Fig. 2. Relay L on energizing prepares the associated group selector for operation by completing a loop from negative conductor, resting contacts of armature $ks1$, armature $l1$, winding of high impedance relay I, left-hand winding of shunt field relay D, resting contacts of armature $ks2$ to the positive conductor. Furthermore at armature $l2$ relay B is operated, thereupon at armature $b1$ extending earth over armature $fr1$ and resting contacts of armature $l1$ to operate relay SJ of the keying trunk relay set. Relay SJ in operating, at armature $sj1$ which closes first, connects up the low resistance upper winding of relay KK to wiper S1 and at armature $sj2$ connects up the high resistance lower winding of relay KK. Consequently if the wiper S1 of the junction finder RF is resting on a contact other than that marked with battery by the operation of armature $b2$, Fig. 3, a circuit will be completed from earth, armature $b2$ of a relay set not in use, bank contact and wiper S1, armature $sj1$, upper low resistance winding of relay KK, armature $kk2$, interrupter springs $rm1$, high resistance winding of relay GJ to battery. A branch of this circuit extends to earth through the lower winding of relay KK but although relay GJ is operable in the circuits traced, its extremely high resistance prevents the operation of relay KK at this time. Relay GJ on operating its armature $gj1$ completes the circuit of the driving magnet RM of the finder switch RF, and as a result of interaction between this magnet and relay GJ the wipers of the switch are advanced until wiper S1 engages the marked contact in which position the keying trunk is associated with the selected junction relay set. When the wipers reach this position relay GJ will be shunted out by battery through the low resistance winding of relay PS and relay KK will be operated over the circuit: earth, armature $sj2$, two windings of relay KK in series, armature $sj1$, wiper S1 and bank contact, armature $b2$, armature $fr3$, winding of relay PS to battery. Relays PS and KK operate in series in this circuit and at armature $kk2$ a guarding and holding circuit is completed by way of the low resistance upper winding of KK, at armature $kk1$ the slow releasing relay SC is operated in series with relay SJ and at armatures $kk3$ — $kk6$ the keying trunk is extended to the associated wipers of the switch RF.

The operation of relay B in the junction

relay set also at armature b_3 started the sender finder switch SF hunting to find a free sender by connecting wiper P1 over armature b_3 , upper low resistance winding of relay KS, armatures ks_8 and fr_4 , interrupter springs sm_1 , high resistance winding of relay GS to battery. If the sender with which the wipers are then associated is busy, earth will be connected to the corresponding P1 contact through the low resistance upper winding of the KS relay of the junction relay set with which the sender is then connected. Relay KS does not operate in this circuit but relay GS at armature gs_1 completes a circuit for the driving magnet SM of the sender finder switch SF which energizes and brings down relay GS by opening interrupter contacts sm_1 . Relay GS and magnet SM interact in known manner until wiper P1 of the switch encounters low resistance battery by way of relay BG, Fig. 5, in a free sender, for instance that shown. Relay GS is then shunted out and the rotation of the sender finder switch is stopped, but relay KS is unable to operate to seize the sender until armature ps_1 is operated when the junction relay set has been found. Thereupon a circuit is completed from earth, armature ps_1 , both windings of relay KS in series, armature b_3 , wiper P1 and bank contact, conductor 12, armatures co_1 and ba_1 , Fig. 5, winding relay BG to battery. Relays BG and KS are operated in this circuit and the latter relay at armature ks_8 completes a holding and guarding circuit by way of its low resistance upper winding. Moreover, at armatures ks_1 and ks_2 the operating circuit of the group selector is transferred to the sender circuit, at armature ks_3 a circuit is prepared for relay FR, and at armatures ks_4 — ks_7 the keying trunk is extended over the wipers of the sender finder switch SF to the seized sender. Relay BG in addition to performing other circuit changes, at armature bg_3 completes a circuit from earth, armature ss_1 , lead 17, armature bg_3 , resting contacts of armature tc_2 , armature ss_3 , winding of relay TA to battery. Relay TA is slightly slow to pull up and on operating at armature ta_3 completes a circuit for relay TB which is also slow to pull up. When relay TB energizes, it completes a circuit for the further slow-to-pull-up relay TC at armature tb_2 and relay TC then locks up at armature tc_2 and brings down relays TA and TB. The operation of relay BG moreover connects up a tone circuit from conductor 13, Fig. 7, condenser Q, armatures ta_2 and tc_1 , conductor 14, armature bg_2 , Fig. 5 conductor 15, bank contact and wiper S_2 , Fig. 3, armature ks_3 , conductor 16, winding of relay FR, right-hand winding of the shunt field relay D to battery. Relay D is provided with a good magnetic circuit and accordingly the tone is induced in the left-hand winding and is thus trans-

mitted over the junction to the operator. The application of tone is made for a period corresponding to the operating time of relay TA, when it is removed at armature ta_2 . After a pause corresponding to the operating time of relay TB it is again applied at armature tb_1 and is then removed at armature tc_1 when relay TC operates. The operator thus receives two short tone signals to indicate that the sender is in condition to register the wanted number. 70 75

The operator will now commence operating her keys to set up the required number, which will be assumed to be 4325. Upon the operation of key 4, a circuit is completed from earth, operated springs of key 4, armature ht_4 , wiper Y and bank contact of the trunk finder TF, winding of relay YR to battery. Relay YR thereupon operates its armature yr_1 thus extending earth over the junction conductor 18, armature hk_5 , wiper Y_1 and bank contact, conductor 19, armature ks_6 , wiper Y_2 and bank contact, conductor 20, wiper DD_5 and first bank contact of digit distributor switch DD, left-hand winding of storage relay MY, winding of common battery feed relay DS to battery. Relays MY and DS operate in series and the former at armature my_1 completes a locking circuit for itself over its right-hand winding and lead 21 to earth at armature bg_4 . Relay DS on operating, at armature ds_1 energizes the driving magnet DDM of the distributor switch DD, so that when the operator releases key 4 and thus opens the circuit of relay DS, the distributor switch wipers will be advanced to the second set of bank contacts, thereby connecting up the second group of storage relays CW, CX, CY and CZ. Moreover when the distributor switch DD takes its first step a circuit is completed from earth at armature bg_6 , Fig. 5, wiper DD_2 and second bank contact, resting contacts of armature ss_2 and winding of relay SS to battery, whereupon relay SS operates and locks up over conductor 21 to earth at armature bg_4 . The operation of relay SS again completes the tone circuit over conductor 13, Fig. 7, condenser Q, armatures ta_1 and ss_5 to conductor 14 and thence as previously traced, so as to provide an indication to the operator that the sender is functioning correctly and that she may proceed to set up the remainder of the digits. After the operating period of relay TA whose circuit is completed at armature ss_3 the tone circuit is opened at armature ta_1 . Relay SS also opens the homing circuit of the sender switch at armature ss_4 and at armature ss_1 completes a circuit from earth, armatures ss_1 and ss_4 , winding of relay CC and resistance 22 to battery. Relay CC is short-circuited intermittently by the impulse springs 23 which may conveniently be operated 10 times per second but when the springs open relay CC operates and 100 105 110 115 120 125 130

at armature $cc1$ opens the short-circuit and extends the impulses to the winding of sender switch driving magnet SDM which is connected to battery through the low resistance relay BP. The wipers S1 and S2 of the sender switch SS are now stepped round their associated banks and as soon as wiper S1 moves off normal, relay SA is operated thereupon at armature $sa1$ removing the short-circuit round impulse springs 24 and thus permitting them to become effective to send impulses over the outgoing conductors. Springs 24 are operated at the same speed as springs 23 and consequently for each impulse sent out for operating the automatic switches the sender switch is advanced one step. When four impulses have been transmitted to the group selector, corresponding to the number keyed, wiper S2 of the sender will engage its sixth bank contact and a circuit may then be traced from earth at wiper C2 and first bank contact of the control switch CS, Fig. 7, conductor 25, armatures $mw2$, $mx2$, $my2$ and $mz3$, lead 4, which is assumed to be connected to lead 4 opposite bank contact 6 and wiper S2 of the sender switch SS, lower winding of relay SZ to battery. Relay SZ accordingly operates and at armature $sz2$ completes a locking circuit for itself, at armature $sz1$, Fig. 4, short-circuits the impulsing springs 24 to prevent the transmission of further impulses at this time, at armature $sz4$ opens the stepping circuit of the sender switch driving magnet SDM, at armature $sz5$ prepares a circuit for its upper winding, and at armature $sz3$ completes an automatic homing circuit for the sender switch from earth by way of bank commoning and wiper S1, armature $sz3$, interrupter springs $sdm1$, winding of magnet SDM to battery through the low resistance relay BP.

The wipers of the sender switch are accordingly driven to the next home position, for instance, contact 13, whereat wiper S1 no longer encounters earth and thus the circuit of the magnet and relay SA is opened. Upon the release of relay SA after its slow period the circuit of relay SZ is also opened and it releases after a slight interval and at armature $sz4$ again completes the circuit for advancing the sender switch. Moreover upon the release of armature $sa3$ magnet CDM will de-energize and accordingly the wipers of the control switch CS will be stepped into engagement with the second set of bank contacts, in readiness to extend earth from wiper C2 over conductor 26 to the second set of storing relay group armatures, which are not shown but are identical with those of the M group, and are multiplied to the sender switch bank in the same manner.

If due to some slight delay in keying, the second digit should not be fully set up at this time, the wipers of the distributor switch DD will be standing on the second set of

bank contacts and a circuit will be completed from earth at armature $bg6$, Fig. 5, wiper DD2 and second bank contact, conductor 27, second bank contact and wiper C3 of the control switch, Fig. 7, conductor 28, armature $sz5$, upper winding of relay SZ to battery. Relay SZ is therefore prevented from releasing and restarting the sender switch until the second digit has been fully received, that is when the distributor switch DD is stepped on to the third set of contacts; hence it is not possible for the sending operation to outrun the storing operation.

When all the digits have been stored, the digit distributor DD will be advanced to fifth position whereupon earth will be connected from armature $bg6$ over wiper DD2 in fifth position, conductor 15, bank contact and wiper S2 of the sender finder SF, armature $ks3$, conductor 16, winding of relay FR, right-hand winding of shunt field relay D to battery. Relay FR thereupon operates and completes a locking circuit for itself at armature $fr1$, at armature $fr2$ prepares the busy flash circuit, at armature $fr4$, Fig. 3, opens a point in the circuit of relay GS and at armature $fr3$ brings down relays PS and KK. Relay KK on releasing, opens the circuit of relays SJ and SC, and since the latter relay is slow to release a circuit is momentarily completed from battery by way of the resistance 30, Fig. 2, armatures $sc1$ and $kk6$, conductor 31 of the keying trunk, armature $yr1$, Fig. 1, winding of relay TR, armature $yr1$, conductor 18 of the keying trunk, armature $kk5$ to earth. Relay TR thereupon operates over the circuit described and at armature $tr1$ brings down relays KT and TS so that at armatures $kt2$ — $kt5$ the keyset is dissociated from the keying trunk which is then available for use by other operators. Relay KS associated with the sender finder SF must clearly remain operated until sending out is completed and its release is normally dependent on the sender.

It may be mentioned that the operation of relay TR in a loop circuit from a battery source at the automatic exchange is convenient as it satisfactorily overcomes any difficulties arising from the fact that the battery voltage employed at the automatic exchange is approximately twice that employed at the manual exchange. It will be seen that as regards the lower two leads of the keying trunk, the operation of the keys instead of connecting earth directly to those leads energizes relays YR and ZR which then connect up the earth, at the same time disconnecting relay TR.

When the sending operation has been completed, the wipers of the control switch CS will advance into the fifth position, whereupon relay CO will be operated from the earthed wiper C2. Relay CO on operating connects a short-circuit across the impulse

leads to the automatic switches at armature c_02 , Fig. 4, thereby holding the switch train and preventing any further pulses being sent, and moreover at armature c_01 opens the circuit of relay BG. On the release of relay BG, armature bg_4 removes earth from the common holding conductor 21, thereby releasing all the storing relays which were operated and also relays BX and SS. On the release of relay SS a homing circuit is completed for the sender switch SS, Fig. 6, while at armatures bg_5 and bg_4 homing circuits are completed for the distributor switch DD, Fig. 5, and the control switch CS, Fig. 7, respectively. As long as current flows through the magnets the battery feed relay BP will be operated and an alternative holding circuit is provided for relay CO over conductor 29, armature bp_1 , armature bg_6 to earth. By this means relay CO is held operated until all switches have reached a home position thereby holding open the circuit of relay BG at armature c_01 in order to prevent the premature re-seizure of the sender. When relay KS releases at the completion of the sending operation owing to the opening of its circuit at armature c_01 battery through the retard LA, Fig. 2, is disconnected from the lower junction conductor at armature ks_9 , thereby indicating on the ordinary supervisory lamp in the cord circuit that sending is completed, while at the resting contacts of armatures ks_1 and ks_2 the negative and positive leads extending to the automatic train of switches are disconnected from the sender and transferred to a holding circuit which includes the high impedance winding of relay I and the left-hand winding of the shunt field relay D. Supervision of the call is now controlled by means of armature d_1 , relay D being operated when the called party answers by the usual reversal of current from the final switch. In case the wanted party is busy at this time, battery will not be reversed from the automatic switches but instead simplex battery will be connected intermittently to the speaking leads thereby effecting the intermittent de-energization of relay I which will flash the supervisory lamp at the operator's position by opening the battery circuit of retard LA. The operator on seeing the lamp flash will inform the calling party that the number he requires is engaged and that he must call again later. In case the operator realizes that she has made a mistake in setting up the number, she may cancel by withdrawing the plug momentarily thereby releasing relay B and thus relays KS and BG. The keying trunk is not released however and the operator may at once set up the proper number, a different sender being now employed. Since in the partially operated sender, relay CO will not have been energized, relay BX is made slow so as to ensure that the sender shall not be

seized before it has completely restored to normal.

Figs. 8 and 9 show the modifications required to the order wire circuit when a slightly different method of operation is employed in which more economical use of the order wire is secured by arranging that the operator tests for a free junction before pressing the order wire key so that the keying trunk is only in use for the actual time that sending is taking place thereover. This represents a considerable economy since the time required to select a free junction may quite well be comparable with the time required to send the wanted number. A difficulty arises, however, in this case owing to the fact that several operators may have selected junctions to a particular automatic exchange and it is important that if they then operate their order wire keys more or less simultaneously the keying trunk shall then be associated with the junction selected by the operator whose keyset has been connected thereto. This is effected by the connection of a special potential over one conductor of the junction to make contacts in an additional bank of the junction finder switch.

Consider now the setting up of a connection from the position shown in Fig. 8 over the junction extending to the equipment shown in Fig. 9. The operator on ascertaining that a call is required to this automatic exchange will test for a free junction in the usual way and on finding one will plug in. This operation will effect the energization of relay L_1 which at armature l_1 prepares the associated first selector for operation and at armature l_2 energizes relay B. Relay B thereupon at armature b_1 completes a circuit for the lower winding of relay KK and relay GJ in series. At armature b_4 prepares the connection of marking potential to the lowermost bank of the switch RF and at armature b_3 sets in operation the sender finder SF to select an idle sender. It will be understood that Figs. 8 and 9 are intended to be associated with Fig. 3, the only difference being that in the modified circumstances the back contact on armature b_2 is no longer necessary. Relay GJ operates as before and interacts with magnet RM to effect the hunting operation of the trunk finder RF.

When the operator now presses the order wire key 01 a circuit is completed for the right-hand winding of relay KT and high resistance relay GT in series and relay GT interacts with the magnet DM to effect the hunting operation of the switch TF. Moreover, at the upper springs of the key 01, battery through the winding of relay TS is connected to the associated contact in the test bank of the switch TF so as to bring the switch to rest when this contact is encountered. As in the arrangement described in Fig. 1, relay TS is then operated in series

with relay KT and at armature t_1 short-circuits the key springs while relay KT at armature kt_1 completes a holding and guarding circuit, at armatures k_2-k_5 connects up the keyset, at armature kt_6 causes the lamp FL to flicker to indicate to the operator that she has obtained possession of the keying trunk and at armature kt_7 connects battery to the tip conductor connected with her headset whence it is extended over the operated contacts of the speaking key, tip of the plug, tip spring of jack, conductor 32, armatures fr_2 and b_4 to the test contact associated with the trunk in the bank of the switch RF. Hence when the wipers reach this contact, a circuit is completed for relay JF which operates and at armature jf_1 completes a switching circuit for relay KK in series with relay PS. Relay GJ is now shunted out and the switch is thus brought to rest and relay KK at armature kk_1 energizes relay SC in series with relay JF, at armature kk_2 completes a holding and guarding circuit, and at armatures kk_3-kk_6 switches the keying trunk through.

The operator will now proceed to key up the required number in the usual manner, thereby effecting the operation of the impulse sender as previously described. When all the digits have been registered, earth will be connected back to effect the operation of relay FR which at armature fr_1 completes a locking circuit for itself, at armature fr_2 disconnects the special marking circuit and prepares a circuit for repeating busy flash and at armature fr_3 brings down relay KK. Accordingly a momentary circuit is completed over the two lower conductors of the keying trunk for relay TR which at its armature tr_1 brings down relays KT and TS thereby freeing the keying trunk. When the full number has been sent out, relay KS is de-energized and the connection is switched through at armatures ks_1 and ks_2 , while at armature ks_9 the operator is given a signal to indicate conclusion of sending.

A further modification is shown in Figs. 10-12, this arrangement also being assumed to work in conjunction with the sender shown in Figs. 4-7. The operating procedure in this case is similar to that just described, that is to say the operator first selects a free junction and then operates the order wire key. In this arrangement, however, the circuits have been somewhat simplified and the necessity for the junction finder has been eliminated, the necessary connections being made directly by relay KK. The momentary marking potential over the selected junction however makes it impossible for the keying trunk to become associated with more than one junction at a time. This arrangement, moreover, removes a possible objection to the arrangement shown in Figs. 8 and 9 that the junction finder RF commences to rotate as soon as the plug is inserted in the junction

while the contact which it is required to find is not marked until the operator presses the order wire key. This difficulty, however, could be readily overcome otherwise by arranging that relay B was dependent for its initial energization on the operation of an earth-connected relay energized by the marking battery potential when the keying trunk was seized.

Referring now to Fig. 10, the procedure is the same as before, viz. that the operator on receiving a request to complete a call to a particular exchange will test with the tip of the plug in the usual manner for a free junction and on finding one will plug in thereon. The arrangement of Fig. 10 shows the group busy tone connected directly to the sleeve of the jack illustrated over chain contacts of the sleeve relays. The operation of plugging in completes a circuit for relay L at the automatic exchange which at armature l_1 prepares the first selector for operation and at armature l_2 prepares a circuit for relay B. When the operator presses the order wire key, at the lower springs of the key a circuit is completed for relay ST which at armature st_1 initiates the hunting operation of the switch TF and at armature st_2 prepares the connection of discriminating battery over the junction. The upper springs of the order wire key serve as in the arrangements previously described to mark the appropriate contact in the test bank of the switch TF. When the required keying trunk is found, relay KT operates and in addition to performing its usual functions, at armature kt_7 opens the circuit of relay ST and connects battery over armature st_2 and the contacts of the speaking key to the tip of the plug. This battery connection, which is only applied as long as relay ST holds up, serves to energize relay B which thereupon at armature b_1 locks up dependent upon armature l_2 . Relay B also at armature b_3 initiates the hunting of the sender finder SF and at armature b_2 completes a circuit for relays PS and KK in series. Relay PS thereupon at armature ps_1 completes a switching circuit for relay KS so as to connect up the seized sender and open the initial circuit of relay B, while relay KK at armature kk_2-kk_5 connects the keying trunk through and at armature kk_1 energizes relay SC.

The operator will now receive the two short periods of tone and will thereupon operate her keys in the usual manner. When all the digits have been registered, earth will be connected up from the sender to operate relay FR which at armature fr_1 locks up dependent upon relay B, at armature fr_2 disconnects the initial energizing circuit of relay B and prepares a circuit for repeating busy flash, at armature fr_3 opens a point in the circuit of relay GS and at armatures fr_4-fr_7 opens the conductors of the keying trunk so as to pre-

vent any possibility of interference in case the keying trunk is taken into use by another operator before sending has been completed and relay KS de-energizes. The operation of relay FR also serves to bring down relay 5 KK so that the usual connection is made to operate relay TR and thus free the keying trunk for use by other operators. When all the digits have been transmitted, relay KS is de-energized and the connection is then 10 switched through, and answering supervision is given the operator by relay D in the usual manner. It may be mentioned that the resting contact of armature Z2 is provided so as to render relay B slow to release in case for 15 any reason relay L should be de-energized momentarily.

What we claim as new and desire to secure by Letters Patent is:

- 20 1. In a telephone system, a manual exchange and a plurality of automatic exchanges, an operator's position in said manual exchange equipped with a numerical keyset, a key corresponding to each of said automatic exchanges, a control trunk extending from said manual exchange to each of said automatic exchanges, a finder switch, and means responsive to the operation of one of said exchange keys for operating said switch to connect said keyset with the control trunk extending to the exchange designated by the operated key.
- 25 2. In a telephone system, a manual exchange and a plurality of automatic exchanges, an operator's position in said manual exchange equipped with a numerical keyset and a key corresponding to each of said automatic exchanges, a control trunk extending from said manual exchange to each of said automatic exchanges, a finder switch, means responsive to the operation of one of said exchange keys for operating said switch to connect said keyset with the control trunk extending to the exchange designated by the operated key, and means for signalling the operator at said position when said connection has been completed.
- 30 3. In a telephone system, a manual exchange and a plurality of automatic exchanges, an operator's position in said manual exchange equipped with a numerical keyset, a key corresponding to each of said automatic exchanges, a control trunk extending from said manual exchange to each of said automatic exchanges, a finder switch, means responsive to the operation of one of said exchange keys for operating said switch to connect said keyset with the control trunk extending to the exchange designated by the operated key, a lamp at said operator's position, and means for intermittently lighting said lamp when said connection has been completed.
- 35 4. In a telephone system, a manual exchange and a plurality of automatic exchanges, an operator's position in said manual exchange equipped with a numerical keyset and a key, and means responsive to the seizure of an idle trunk line at said operator's position for causing said switch to associate said control trunk with the seized trunk line.

changes, an operator's position in said manual exchange equipped with a keyset and a plurality of keys, one for each of said automatic exchanges, a control trunk extending from said manual exchange to each of said automatic exchanges, means responsive to the operation of one of said exchange keys for connecting said keyset to the control trunk extending to the exchange designated by the operated key, a plurality of registers in the automatic exchange, means controlled by said keyset for operating said registers to record the called number, a release key at said operator's position, and means for disconnecting said keyset from said control trunk responsive to the operation of said release key or responsive to the registration of the complete called number.

5. In a telephone system, a manual and an automatic exchange connected by a control trunk and a plurality of trunk lines, a plurality of operators' positions in said manual exchange each equipped with a keyset, means controlled from any one of said operators' positions for connecting the keyset at that position to said control trunk, an automatic switch associated with the control trunk in said automatic exchange, and means responsive to the seizure of an idle trunk line at said operator's position for causing said switch to associate said control trunk with the seized trunk line.

6. In a telephone system, a manual and an automatic exchange connected by a control trunk and a plurality of trunk lines, an operator's position in said manual exchange equipped with a numerical keyset and a key, and means responsive to the seizure of an idle trunk at said operator's position and to the operation of said key for connecting a distinguishing potential to one conductor of the seized trunk line in the manual exchange, for connecting said keyset to said control trunk in the manual exchange, and for associating said control trunk with the seized trunk line in the automatic exchange dependent upon the presence of said distinguishing potential on one conductor of the trunk line.

7. In a telephone system, a manual and an automatic exchange connected by a control trunk and a plurality of trunk lines, a plurality of operators' positions in said manual exchange each equipped with a keyset, means controlled from any one of said operators' positions for connecting the keyset at that position to said control trunk, an automatic switch associated with the control trunk in said automatic exchange, and means responsive to the seizure of an idle trunk line at said operator's position for connecting a marking potential over one conductor of the seized trunk line to mark the seized trunk line in the banks of said hunting switch and for operating said switch to the marked position to

associate the control trunk with the seized trunk line.

8. In a telephone system, a manual and an automatic exchange connected by a control trunk and a plurality of trunk lines, a plurality of operators' positions in said manual exchange each equipped with a keyset, means controlled from any one of said positions for associating the keyset at that position with

10 said control trunk, means responsive to the seizure of an idle trunk line for associating the control trunk with the seized trunk line in the automatic exchange, an automatic switch, a plurality of register senders, and

15 means also responsive to the seizure of said trunk line for causing said switch to associate an idle one of said register senders with the control trunk and the seized trunk line.

9. In a telephone system, a manual and 20 an automatic exchange connected by a control trunk and a plurality of trunk lines, a plurality of operators' positions in said manual exchange each equipped with a keyset, means controlled from any one of said positions for 25 associating the keyset at that position with said control trunk, an automatic switch and a plurality of register senders in said automatic exchange, means responsive to the seizure of an idle trunk line at said operator's 30 position for associating the control trunk with the seized trunk line in the automatic exchange and for causing said automatic switch to associate an idle register sender therewith, and means responsive to said last 35 means for returning a tone signal to the manual exchange to inform the operator that her keyset has been connected to an idle register sender.

10. In a telephone system, a manual and 40 an automatic exchange connected by a control trunk and a plurality of trunk lines, an operator's position in said manual exchange equipped with a keyset, means for connecting said keyset to said control trunk, a plurality 45 of register senders in said automatic exchange, means responsive to the seizure of an idle one of said trunk lines at said operator's position for associating said trunk line and said control trunk with an idle one of said 50 register senders, means controlled by said keyset for operating said register sender to register the digits of the called number, and means responsive to the registration of the first digit for starting said sender to retransmit the registered digit.

11. In a telephone system, a manual and 60 an automatic exchange connected by a control trunk and a plurality of trunk lines, an operator's position in said manual exchange equipped with a keyset, means for connecting said keyset to said control trunk, a plurality 65 of register senders in said automatic exchange, means responsive to the seizure of an idle trunk line by the operator at said position for associating the seized trunk line and

said control trunk with an idle one of said register senders, means controlled by said keyset for operating said register sender to register the digits of the called number, and means responsive to the registration of the 70 first digit for returning a distinctive tone signal to the operator.

12. In a telephone system, a manual and an automatic exchange connected by a control trunk and a plurality of trunk lines, a plurality of operators' positions in said manual exchange each equipped with a keyset, means controlled from any one of said positions for connecting the keyset at that position with any said control trunk, a plurality 75 of register senders in said automatic exchange, means responsive to the seizure of an idle one of said trunk lines at said operator's position for associating the control trunk and the seized trunk line with an idle one of said register senders, means controlled by said keyset for operating said register sender to register the digits of the called number and to retransmit the same, and means for signalling the operator at said position during 80 the time that said register sender is connected to the trunk line.

13. In a telephone system, a manual and an automatic exchange connected by a control trunk and a plurality of trunk lines, a plurality of operators' positions in said manual exchange each equipped with a keyset, means controlled from any one of said operators' 95 positions for connecting the keyset at that position to said control trunk, a plurality of register senders in said automatic exchange, means responsive to seizure of an idle one of said trunk lines at said position for associating the seized trunk line and the control trunk with an idle one of said register senders, means for operating said register sender over the control trunk to register the digits of the called number, and means for releasing 100 said control trunk as soon as the complete number has been registered.

14. In a telephone system, a manual and an automatic exchange connected by a control trunk and a plurality of trunk lines, a plurality of operators' positions in said manual exchange each equipped with a keyset, means controlled from any one of said operators' positions for connecting the keyset at that position to said control trunk, a plurality of register senders in said automatic exchange, means responsive to the seizure of an idle one of said trunk lines at said operator's position for associating the seized trunk line and the control trunk with an idle one of said register senders, means for operating said register sender over the control trunk to register the digits of the called number, a relay in that manual exchange, and means for operating said relay responsive to the registration of the complete number to disconnect said keyset from the control trunk.

15. In a telephone system, a manual exchange and a plurality of automatic exchanges, a plurality of operators' positions in said manual exchange each equipped with a
5 keyset, a plurality of exchange keys at each position, one for each automatic exchange, a control trunk and a plurality of trunk lines extending from said manual exchange to each of said automatic exchanges, a plurality of
10 register senders in each automatic exchange, means responsive to the operation of one of said exchange keys at any one of said operators' positions for connecting the keyset at that position with the control trunk ex-
15 tending to the exchange designated by the operated key, and means responsive to the seizure of an idle one of the trunk lines ex-
tending to the selected exchange for associating the control trunk and the seized trunk
20 line with an idle register sender in that exchange.

16. In a telephone system, a manual exchange and a plurality of automatic exchanges, an operator's position in said manual exchange equipped with a plurality of keys, one for each automatic exchange, a control trunk and a plurality of trunk lines connecting said manual exchange with each of said automatic exchanges, means responsive
25 to the operation of one of said keys for associating the operator's position with the control trunk extending to the exchange designated by the operated key, and means re-
sponsive to the seizure of an idle trunk line
30 extending to said exchange for associating the control with the seized trunk line in the automatic exchange.

In testimony whereof I have signed at Chicago, Ill., U. S. A., this 9th day of April,
40 1930.

JOHN ELLIS OSTLINE.

In testimony whereof I have signed at Liverpool, England, this 27th day of March,
45 1930.

REGINALD TAYLOR.

In testimony whereof I have signed at Florence, Italy, this 24th day of March, 1930.

CHARLES EDMUND BEALE.
